UNITED STATES PATENT OFFICE.

ROBERT A. CARTER, JR., OF BAY RIDGE, BROOKLYN, NEW YORK.

METHOD OF AND APPARATUS FOR AUTOMATIC CLEANING AND AUTOMATIC CONTROL OF MECHANICAL GRATES.

Application filed June 12, 1923. Serial No. 644,880.

To all whom it may concern:

Be it known that I, ROBERT A. CARTER, Jr., a citizen of the United States, residing at Bay Ridge, Brooklyn, county of Kings, 5 State of New York, have invented certain new and useful Improvements in Methods of and Apparatus for Automatic Cleaning and Automatic Control of Mechanical Grates, of which the following is a specification taken in connection with the accompanying drawings.

My invention relates to the method of automatic cleaning and also to automatically controlling a mechanical grate. My 15 invention broadly consists in the method of controlling the operation of the grate, by means of the heat of the fire bed.

My invention further relates to controlling the cleaning of different portions of 20 the undersurface of the fire bed by means of the heat of the particular portion of the fire bed. That is, by my invention the heat of different portions of the fire bed controls the operation of the grate.

25 My invention further relates to a water gas generator which can be continuously operated by means of my invention.

My invention further relates to an automatic controlled mechanical grate that will 30 automatically cease operating, either in whole or in part, when owing to too rapid operation it has started to draw down hot fuel instead of ashes and clinkers.

I preferably employ my invention with 35 a water gas machine, although it is to be understood that my invention is not to be limited to this use. It may be applied upon boilers, stills, producers, blast furnaces, and the like wherever a mechanically operated 40 grate may be used to withdraw the ashes from beneath a fire.

In the operation of a water gas generator it is the practice, now generally in use, to 45 equip the generator with stationary bars, set with a uniform distance between them, upon which the fuel bed rests.

It is customary in the operation of a 50 water gas generator to feed fuel each hour as the fuel in the generator is consumed and at the close of from six to eleven hours to discontinue the operation, open the cleaning doors and remove the accumulation of ash and clinker from beneath the fire by

hand. This method of ash removal requires from 60 to 120 minutes for a gang of from 55 4 to 6 men; is very hot, arduous labor; is usually attended with considerable loss of fuel from the generator and is attended with an upsetting of the heat balance in the carburetor and superheater to which the above 60 mentioned generator is attached.

Many attempts have been made to introduce continuous mechanical removal of the ash and the clinker; first to save labor, second to save the fuel consumed and lost during 65 cleaning period, third to save the operating time lost during the cleaning, fourth to maintain uniform conditions of operation in the generator and fifth to maintain uniform heat in the carburetor and super- 70 heater.

It has been attempted to use mechanically 75 operated grates with water gas generators. In these mechanical grates the grate bars are rotated by a worm wheel, gearing with a worm shaft, the grate bars being preferably arranged in pairs. In practice such a mechanical grate has been found unsatisfactory. While such a mechanical grate is positive in its action and continuous in its 80 operation, it has no flexibility and cannot adjust itself to the varying conditions and needs of a water gas generator, or any similar device where the fuel and consumption is not uniform.

If the fuel used in a water gas generator 85 were uniform from day to day and from hour to hour, in the percentage of its ash content; and if this increment of ash were 90 constant in character and the rate of production, and likewise the rate of fuel consumption were constant at all times; and if the rate of fuel consumption and ash accumulation were the same in the center of the machine as in points nearer the walls, 95 then it would be possible that a grate of this nature could be set at the proper rate of rotation to withdraw the ash as it accumulates; on the one hand not allowing the ash to build up above the grate, and on 100 the other hand not withdrawing and wasting the incandescent fuel.

But such conditions with regard to the 105 character of the fuel and ash accumulation do not exist in practice. Wide variations occur in percentage of ash in fuel, in the rate

of production and in the consumption of fuel in different parts of the generator. The rate of movement which is suitable at one time, is not suitable at another, and the 5 rate of movement which is suitable at one point in the grate area, is not suitable at another. Therefore, in the operation of any of the now known mechanical grates, while the ash is building up at one point, the fire 10 is being pulled down from the fire bed at another point and wasted.

It is this latter feature, among others, which has prevailed against the commercial application of mechanical ash removal 15 grates to water gas generators.

When at any point there is a tendency for the ash to be removed faster than it is produced, the fire comes in contact with the grate and then the hot fuel is withdrawn at that point heating the iron or steel of which the grates are made to an extent which makes them warp, or bend, or buckle, or twist, invariably necessitating the shutting down of the machine and the removal of the grate with the attendant expense of its replacement.

By my invention I so control the operation of the grate that either in whole, or in part, it will automatically cease to operate when, owing to too rapid operation, there is a tendency to withdraw incandescent fuel.

With my invention, when one of the bars of the grate, due to withdrawing the ash 35 too rapidly, tends to become too hot, that particular grate bar is automatically made to cease rotating. The effect is first, that no damage is done to that part of the grate; second, there is a cooling off of that grate bar owing to the accumulation of ash above it resulting from continued operation of the generator, thus permitting that grate bar automatically to take up again its suspended operation.

45 This automatic control of the grate bars is accomplished in my invention by using the different degrees of heat of different portions of the fire bed itself, to control the amount of cleaning that the different 50 portions of the fire bed shall be subjected to.

I have shown by way of illustration one adaption of my invention in which the control of the cleaning is effected by means 55 of the different portions of the undersurface of the fire bed heating and expanding the different grate bars. In the particular form shown in the drawings, by way of illustration, it is the linear expansion of 60 the different grate bars themselves, when heated beyond their normal temperature, which automatically prevents the removal of hot coals from that portion of the fire

bed above them, by causing that bar or bars to cease rotating. This will then permit new ash and new clinker to form above the particular grate bar, thereby removing it from the live coals, and consequently permitting it to cool. As soon as it is cooled to the predetermined temperature it will again be automatically thrown into gear, and will again clean that particular portion of the fire bed, it being understood that preferably each one of my grate bars is separately and automatically controlled.

65 My invention is adapted for general application and a wide range of structures can be employed, all of which will come within the terms of my invention.

70 For purpose of illustration, and to show one adaptation of my invention, but of course, not the only one, I have shown it in connection with a water gas machine.

75 My invention further relates to certain methods, combinations and sub-combinations and details of construction all of which will be more fully hereinafter described and pointed out in the claims.

80 In the accompanying drawings the same reference numerals refer to similar parts in the several figures.

85 Fig. 1 is a horizontal section through a water gas machine, the grate bars and some of the worm wheels being shown in plan;

90 Fig. 2 is a vertical section substantially on the line 2—2 of Fig. 1;

95 Fig. 3 is a vertical section, on an enlarged scale, showing one form of clutch which may be employed;

100 Fig. 4 is a vertical section, on an enlarged scale, of a detail showing the adjustable thrust bearing to adjust the limit of travel of the grate bar in that direction.

105 In the drawings 1 is a water gas machine provided with a plurality of rotating grate bars 2, 2, the bars being preferably arranged in pairs and adapted to rotate towards each other. On these bars, which are preferably square in cross-section for most of their length, I mount a plurality of disks 3, 3 arranging them staggered with relation to each other. Each disk is provided with a cutaway portion 110 4, 4. The disks are arranged in pairs and each pair revolves towards each other, so that the cutaway portions act as cutting members and remove the accumulated ash and clinker above them; the weight of the fire bed serving to press new ash and new clinker into the path of the disks, as the fire burns and the grate bars rotate. The 115 ash and clinker fall into the ash pit or bin 21 and are removed therefrom in any suitable manner.

120 125 It has been previously pointed out that

in most all fire beds, and particularly so in a water gas generator, neither the fuel, nor the ash content is uniform; nor is the accumulation of the ash and clinker the same at the center of the fire bed and at the circumference.

By my invention I automatically control the rotation of the grate bars 2, 2 that they will only be rotated to stoke the fire bed when there is sufficient accumulation of ash and clinker above them to warrant their rotation and without withdrawing live coal, each grate bar being independently and automatically controlled by the temperature of the particular portion of the fire bed which it supports. This will permit all the grate bars 2, 2 to be rotated at the same time, or any one of them, the others being, for the moment, immovable.

In the apparatus, which I have shown as one embodiment of my invention, each grate bar 2 has a round portion 5 mounted in the bearing 6. On this portion 5 of the grate bar 2 is loosely mounted a worm wheel 7 to which is secured the concave member 8 of a cone clutch. To prevent lateral movement of the worm wheel 7, with its clutch member 8, I provide it with a groove 9 within which fits retaining members 10, 10 secured to the bearing 6 by means of the bolts 11, 11. On the end of the cylindrical shaft 5, of the grate bar 2, is immovably secured the convex clutch member 12 of the cone clutch by means of the pin 13. The clutch members 8 and 12 are normally pressed into engagement by the spring 14.

The adjustable thrust bearing 15, Fig. 4, is withdrawn from the recess 16 in the bar 2 and is set at a predetermined position when the bar is cold so that when it starts to heat up, the expansion will be in that direction first, until the limiting temperature is reached, when being resisted by the thrust bearing 15 all subsequent movement will be in the other direction, compressing the spring 14 and releasing the clutch.

A worm shaft 18 is mounted at right angles to the grate bars 2, 2 and is provided with pairs of right and left worms 19, 19 (only one of them being shown) so that the grate bars 2, 2 will operate in pairs and rotate towards each other when both are rotated by the worm shaft 18.

In the operation of my device, as here illustrated, the worm shaft 18 always rotates each one of the worm wheels 7, and normally will rotate each one of the grate bars 2 by means of the spring 14 engaging the clutch members 12 and 8. When, however, any one or more of the grate bars 2, 2 has removed all the ash and clinker upon it and has thereby become unduly heated by

proximity with the live coals of the fire bed, that grate bar 2 will expand and be given a linear movement, which is resisted in one direction by the thrust bearing 15, so that it can only expand linearly against the action of the spring 14. In so expanding, however, it withdraws the clutch member 12 from engagement with the clutch member 8, permitting the latter clutch member with the worm wheel 7 to rotate idly, without rotating the particular grate bar 2 upon which it is mounted. This will then permit new ash and new clinker to accumulate above this particular grate bar 2 which will then be stationary, and as this accumulation increases the grate bar is cooled. The moment that it has cooled to its predetermined temperature it will contract, aided by the tension of the spring 14, and will immediately again cause the clutch members 12 and 8 to engage so that that particular grate bar will again be operated to remove ash and clinker. This is true of all the grate bars 2 which are all separately and automatically controlled by the temperature of the fire bed immediately above them.

This not only prevents the grate bars 2 from warping, bending, buckling or twisting, requiring the water gas machine to be shut down while they are being removed, but it permits the continuous operation of the water gas machine, with any variety of fuel and without wasting live coals.

Having thus described this invention in connection with an illustrative embodiment thereof, to the details of which I do not desire to be limited, what is claimed as new and what is desired to secure by Letters Patent is set forth in the appended claims.

What I claim is:—

1. The method of automatically cleaning a fire bed, consisting in removing the ash and clinker, and employing the heat of the fire bed to itself directly control the rate of removal of the ash and clinker from said fire bed.

2. The method of automatically cleaning a fire bed, consisting in removing the ash and clinker, and employing the heat of the fire bed to itself directly control the rate of removal of the ash and clinker from one or more parts of the said fire bed.

3. The method of automatically cleaning a fire bed, consisting in removing the ash and clinker, and employing the heat of the fire bed to itself directly control the rate of removal of the ash and clinker from one or more parts of the said fire bed, without interfering with the cleaning of other parts of said fire bed.

4. The method of automatically cleaning a fire bed consisting in operating grate bars

to remove ashes and clinkers and employing the heat of the fire bed to automatically discontinue the operation of one or more of the grate bars when the proper amount of 5 ash and clinker have been removed from the fire bed above said grate bar or grate bars.

5. The method of automatically cleaning a fire bed consisting in moving grate bars to remove ash and clinker and employing 10 the heat at different portions of the furnace to control the movement of the different grate bars.

6. The method of automatically cleaning a fire bed consisting in moving grate bars 15 to remove ash and clinker, and employing the expansion of the grate bars to prevent movement temporarily of one or more of the grate bars to permit new ash and new clinker to again build up above said bar or 20 bars.

7. The method of automatically cleaning a fire bed consisting in rotating grate bars to remove ash and clinker, and employing the heat of the furnace to expand one or more 25 of the grate bars to prevent rotation of said bar or bars when they have reached a certain predetermined temperature to permit new ash and new clinker to again form above them.

30 8. The method of automatically cleaning all or different portions of the under surface of a fire bed, by removing all or fractional parts of the ash and clinker, consisting in automatically controlling the rate of cleaning 35 by the temperature of different portions of the under surface of the fire bed.

9. The method of cleaning a water gas generator consisting in automatically removing ashes and clinkers from the fire bed by 40 moving the grate bars on which the fire bed rests, and employing the heat of the fire bed to automatically control the movement of the grate bars so that one or more of them may be from time to time rendered immovable 45 able to permit new ash and new clinker to accumulate above them.

10. The method of cleaning a water gas generator consisting in automatically removing ashes and clinkers from the fire bed 50 by rotating the grate bars on which the fire bed rests, and employing the heat of the fire bed to automatically control the rotation of the grate bars so that one or more of them may be from time to time rendered immovable 55 able to permit new ash and new clinker to accumulate above them.

11. The combination in an automatically controlled mechanical grate, of rotatable grate bars, means to rotate them, and automatic means controlled by the expansion of 60 said grate bars to control the rotation of said grate bars.

12. The combination in an automatically

controlled mechanical grate, of movable grate bars, and means controlled by the heat 65 of the grate bars to automatically stop the movement of said grate bars.

13. The combination in an automatically controlled mechanical grate of rotating grate bars, means to rotate them, and automatic means controlled by the expansion of 70 the grate bars to disconnect and connect one or more of said grate bars from said rotating means.

14. The combination in an automatically 75 controlled mechanical grate of grate bars adapted to rotate in pairs towards each other, means to rotate said grate bars, discs on each grate bar, and automatic means controlled by the degree of heat of the grate bar to stop 80 the rotation of one or more of said grate bars.

15. In a water gas machine adapted for continuous operation, the combination of rotating grate bars, means to rotate said bars, 85 and automatic means controlled by the heat at different portions of the undersurface of the fire bed to stop the rotation of one or more of said grate bars to permit new ash and new clinker to again accumulate upon said 90 bar or bars.

16. In a water gas machine adapted for continuous operation, the combination of rotating grate bars, means to rotate said bars, and automatic means controlled by the expansion 95 of the grate bar or bars to stop the rotation of one or more of said grate bars to permit new ash and new clinker to again accumulate upon said bar or bars.

17. In an automatic controlled mechanical 100 grate the combination of rotating expandible grate bars, driving members loosely mounted on the expandible grate bars, driven members connected to the expandible grate bars, spring means to normally connect the driving and driven members, when the grate bars are at their normal temperature and condition, said driving and driven members being disconnected when the grate bars are expanded by abnormal heat, and means to 105 rotate the driving member.

18. In an automatic controlled mechanical 110 grate the combination of rotating grate bars, worm wheels loosely mounted on the grate bars, clutch members connected to the worm wheels, clutch members connected to the grate bars, a worm shaft, springs to normally press the clutch members into engagement to rotate the grate bars, the expansion 115 of the grate bars against the action of the springs serving to disconnect the clutch members when the grate bars become overheated, the clutch members again engaging when the grate bars cool and contract.

19. In an automatic controlled mechanical 120 grate the combination of rotating grate

bars, worm wheels loosely mounted on the grate bars, clutch members connected to the worm wheels, clutch members connected to the grate bars, a worm shaft, springs to normally press the clutch members into engagement to rotate the grate bars, the expansion of the grate bars against the action of the springs serving to disconnect the clutch members when the grate bars become overheated,

the clutch members again engaging when 10 the grate bars cool and contract and means of adjustment to establish the temperature at which the clutch will disengage.
